L. C. NORTON.
COMBINED DOOR STOP AND DOOR HOLDER
APPLICATION FILED OCT. 10, 1912.

1,071,172.

Patented Aug. 26, 1913.

UNITED STATES PATENT OFFICE.

LEWIS C. NORTON, OF CHICAGO, ILLINOIS, ASSIGNOR TO NORTON DOOR CHECK COMPANY, OF CHICAGO, ILLINOIS, A CORPORATION OF WEST VIRGINIA.

COMBINED DOOR-STOP AND DOOR-HOLDER.

1,071,172.

Specification of Letters Patent.

Patented Aug. 26, 1913.

Application filed October 10, 1912. Serial No. 724,922.

To all whom it may concern:

Be it known that I, LEWIS C. NORTON, a citizen of the United States, residing at Chicago, county of Cook, State of Illinois, have invented an Improvement in Combined Door-Stops and Door-Holders, of which the following description, in connection with the accompanying drawing, is a specification, like characters on the drawing representing like parts.

This invention has for its object to provide a novel door-holding device by which a door may be securely held open.

My invention may be incorporated in a door-holding device which is separate from a door check, or it may be incorporated in the door check.

The device comprises two friction disks arranged so that when the door is opened they are clamped together to frictionally hold the door in its open position, and means whereby the opening movement of the door will cause the friction disks to be clamped together while the closing movement of the door will release the friction disks from each other. I have in the drawings shown my invention as embodied in a door stop which is separate from the door-checking device and also in a door stop which is associated with the door-checking device.

In the drawings Figure 1 is a perspective view showing a combined door-checking device and door stop; Fig. 2 is a similar view showing a door stop without the checking device; Fig. 3 is an enlarged sectional view on the line $x-x$, Fig. 2; Fig. 4 is a sectional view through the door jamb on the line $y-y$, Fig. 2, showing the door closed.

1 designates a door and 2 the door casing. Referring first to Fig. 2 which shows the door stop separate from a door-checking device said stop comprises two arms 3 and 4, one of which is secured to the door and the other of which is secured to the door casing, and each of which is provided at its inner end with a friction face adapted to frictionally engage that of the other member.

In the embodiment shown in Figs. 2 and 3, each arm is provided at its inner end with a head, said heads being designated 5 and 6, respectively. Each head is formed with a flat frictional face 7, said faces being arranged to have contact with each other.

One of the heads, the head 5 in the embodiment herein shown, carries a screw-threaded

stud 8, the screw-threaded portion 9 of said stud extending into a screw-threaded bore in the head 6 and having screw-threaded engagement therewith. The stud 8 thus forms a pivotal connection between the arms 3 and 4. The arm 3 is pivotally connected to one side of the door 1 in some suitable way, as by having pivotal connection with a bracket 10 which is secured to the door. The outer end of the arm 4 is pivotally connected to the door casing 2 and this can be readily accomplished by pivotally connecting said arm to a plate 11 which is secured to the door casing. The construction is such that when the door is closed the two arms 3 and 4 are folded together substantially into parallelism, as shown in Fig. 4, while when the door is opened said arms swing into the position shown in Fig. 2. Owing to the screw-threaded connection between the stud 8, which is non-rotatable in the head 5, and the head 6, the turning movement of the two heads relative to each other as the door opens and closes will move the friction faces toward and from each other. The construction of the screw-threads 9 is such that during the opening movement of the door the relative turning movement between the head 6 and screw-thread 9 advances the screw into the head, thus bringing the friction faces 7 together. The stud is so adjusted that these friction faces will be forced into firm frictional contact when the door reaches its desired open position, and the frictional contact is sufficient to hold the door in this position, as shown in Fig. 2. In order to close the door it is given a quick initial movement sufficient to overcome the friction between the faces 7, and when this has been accomplished the door can be readily closed. During the closing movement the faces 7 are separated from each other by the action of the screw-thread 9. The adjacent faces of the heads 5 and 6 can be provided with friction washers 12 of leather or other suitable material if desired.

I propose to make the stud 8 adjustable in the head 5 so as to provide for holding the door in any desired open position. It will readily be seen that if the stud 8 is adjusted upwardly through the head 5, then the door will swing farther open before the friction faces come into frictional contact, while if the screw 9 is withdrawn down-

wardly into the head 5 the door will be brought to rest after having moved through a less distance. The stud 8 is shown as splined to the head 5 and is provided at its lower end with a set nut 15 by means of which it may be adjusted in the head and held in adjusted position.

My invention can be applied to the arms of a door check of that type which comprises in its construction two pivotally-connected arms which have a swinging motion relative to each other as the door opens and closes. In Fig. 1 I have shown at 16 a door check of a type which is now commonly used and which comprises in its construction two arms 30 and 40 pivotally connected together, and one of which is connected to the check 16 and the other to the door casing. In applying my invention to this form of door check, the two arms 30 and 40 are formed at their inner ends with the heads 5 and 6 that are similar in construction to the heads 5 and 6, shown in Figs. 2 and 3, said heads being pivotally connected by the screw-threaded stud 8. The operation of this embodiment of my invention is the same as that described above, for so far as the friction faces of the heads 5 and 6 are concerned they operate to hold the door open equally well whether the arms to which the heads are connected form the two arms of a door check 16 or whether they are separate arms independent from a door check, as shown in Figs. 2 and 3.

While I have illustrated some embodiments of my invention I do not wish to be limited to the constructional features shown, or in any way except by the appended claims.

Having fully described my invention, what I claim as new and desire to secure by Letters Patent is:—

1. In a door stop, the combination with two arms, each having a friction face adapted to engage that of the other arm, means connecting one arm pivotally to the door and the other arm pivotally to the door frame, means constituting a pivotal connection between said arms which permits the arms to swing relative to each other as the door opens and closes, said means constructed to cause the friction faces to move toward each other during the opening movement of the door.

tively toward each other during the opening movement of the door and away from each other during the closing movement of the door, and means for adjusting said pivotal connection to cause the friction faces to firmly engage each other when the door has been opened to any desired extent.

2. In a door stop, the combination with two arms, each having a friction face adapted to engage that of the other arm, means for pivotally connecting said arms to the door and the door frame, respectively, and a screw-threaded stud carried by one arm and non-rotatable relative thereto, said stud having screw-threaded engagement with the other arm whereby as the door is opened and closed the relative turning movement of said stud and said last mentioned arm will cause said friction faces to move toward and from each other.

3. In a door stop, the combination with two arms, each provided with a head having a friction face, means for pivotally connecting said arms to the door and the door frame, respectively, a stud carried by one head and non-rotatable relative thereto, said stud having screw-threaded engagement with the other head whereby as the door opens and closes the frictional faces are moved toward and from each other, and means for adjusting said stud in the first-named head.

4. In a door stop, the combination with two arms, each having a friction face adapted to engage that of the other arm, means connecting one arm pivotally to the door and the other arm pivotally to the door frame, and means constituting a pivotal connection between said arms which permits the arms to swing relative to each other as the door opens and closes, said means constructed to cause the friction faces to move toward each other during the opening movement of the door.

In testimony whereof, I have signed my name to this specification, in the presence of two subscribing witnesses.

LEWIS C. NORTON.
